(57) CLAIM

The ornamental design for the fisherman's tool and handle therefor, as shown and described.

DESCRIPTION

FIG. 1 is a top plan view of the handle portion of the fisherman's tool and handle therefor showing our new design;

FIG. 2 is a left side elevational view thereof, with the right side elevational view being a mirror image thereof;

FIG. 3 is a bottom plan view thereof;

FIG. 4 is a front elevational view thereof; and,

FIG. 5 is a rear elevational view.

The broken line disclosure is for illustrative purposes only and forms no part of the claimed design.
